A. E. Miller,
Inventor

By *Merle A. Price*
Attorney

UNITED STATES PATENT OFFICE.

ARTHUR E. MILLER, OF MONTPELIER, VERMONT.

KEY-RING HOLDER.

Application filed March 26, 1924. Serial No. 702,040.

To all whom it may concern:

Be it known that I, ARTHUR E. MILLER, a citizen of the United States, residing at Montpelier, in the county of Washington 5 and State of Vermont, have invented certain new and useful Improvements in Key-Ring Holders, of which the following is a specification.

This invention relates to new and useful 10 improvements in key ring holders which are especially adapted to be worn on the belt of a person, means being provided for preventing the accidental displacement of the key ring holder when the same is supported 15 thereby.

A still further object of the invention is to provide a key ring holder of the above mentioned character, wherein a safety lock is associated therewith for retaining the 20 key ring in position on the holder against accidental displacement therefrom, the safety lock being of such construction as to permit the same to be readily and easily actuated for releasing the same from a 25 locked position whenever it is necessary to remove the key ring from the holder.

A still further object of the invention is to provide a key ring holder of the above mentioned character, which is simple in 30 construction, inexpensive, strong and durable and further well adapted for the purposes for which it is designated.

Other objects and advantages of this invention will become apparent during the 35 course of the following description.

In the accompanying drawing forming a part of this specification, and in which like numerals designate like parts throughout the same,

40 Figure 1 is a front elevation of my key ring holder showing the same in position on a belt,

Figure 2 is a view taken on the line 2—2 of Figure 1, and

45 Figure 3 is a sectional view taken on approximately line 3—3 of Figure 1.

In the drawing wherein for the purpose of illustration is shown the preferred embodiment of my invention, the numeral 1 50 designates generally my key ring holder and the same is formed preferably of a single strip of metal. The upper portion of the strip of metal 1 is provided with an attaching portion 2 the same being of such construction as to fit snugly around the belt

A in the manner as clearly shown in the drawing. The attaching portion is further of such construction as to permit the same to be frictionally in engagement with the belt thus preventing the free movement of 60 the same thereon and holding the key ring holder in the desired position on the belt. The lower portion 3 of the key ring holder 1 is bent back upon itself to provide the key ring receiving and retaining loop 4 at 65 the bottom of the strip in the manner as clearly shown in Figure 2 of the drawing. The upper portion of the bent back portion 3 extends inwardly adjacent the intermediate portion of the strip 1 and is curved outwardly in the manner shown at 5 in the drawing to permit the key ring to readily be received between the strip 1 and the bent back portion 3 thereof. 70

For the purpose of retaining the key ring 75 in position in the looped portion 4 I provide the safety lock which comprises the substantially U-shaped member 6. The U-shaped member 6 is adapted to operate in the elongated slot 7 provided in the bent 80 back portion 3 and one of the arms 7 of the U-shaped member 6 is adapted to extend on the outer face of the bent back portion 3 as is also a portion of the crown 8 of the substantially U-shaped member 6. The U-shaped member 6 is furthermore pivotally supported on the bent back portion 3 by means of the transversely extending pin 9 which is supported in a suitable ear 10 provided on the outer face of the bent back 90 portion 3, and extends further through the crown portion of the U-shaped member. The outer face of the other arm 11 of the U-shaped member 6 is substantially flat to co-operate with the inner face of the intermediate portion of the strip 1 when the lock is in a locked position in the manner as shown in Figures 2 and 3 of the drawing. For the purpose of actuating the locking member I provide the outer end of the arm 11 of the inverted U-shaped member 6 with the ball-shaped head 12. 95

In use, when it is desired to place a key ring on the key ring holder, the inverted U-shaped locking member 6 is swung out 105 of engagement with the intermediate portion of the strip 1 by raising upwardly on the ball-shaped head 12 and causing the arm 11 to pass through the slot 7 formed in the bent back portion 3. In this manner 110

the outer face of the crown portion of the inverted U-shaped member 6 will extend substantially flush with the inner face of the bent back portion 3 and the key ring 5 may then be passed over the bent back portion and the outwardly extending arms of the inverted U-shaped member so that the key ring may be disposed in the looped portion 4. When the key ring is in position in the 10 looped portion, the ball shaped head 12 is then moved downwardly so as to cause the arm 11 to swing inwardly through the slot 3' until the outer face of the arm 11 is flush with the inner face of the strip 1 in the manner as shown and thereby will prevent the possibility of the key ring from working up out of the bent back portion and being accidentally removed from the 15 holder.

20 It will thus be seen from the foregoing description, that a safety key ring holder has been provided which may be easily and quickly actuated for placing a key ring thereon and furthermore permitting the 25 same to be removed therefrom. It is to be understood of course, that the arms of the inverted U-shaped locking member are of such length as to permit the key ring to pass over the same when the arms are 30 disposed in a substantially horizontal position and thus will not interfere with the free movement of the key ring thereover.

35 A key ring holder of the above mentioned character, may be manufactured at a very low cost and will further be strong and durable and at all times positive in its locking action.

40 While I have shown the preferred embodiment of my invention, it is to be understood that various changes in the size, shape and arrangement of parts may be resorted to without departing from the spirit of the invention and the scope of the appended claims.

45 Having thus described my invention, what I claim is:—

50 1. A key ring holder comprising a strip of metal having its upper end provided with attaching means for supporting the same on the belt of a person, the lower portion of said strip being bent back upon itself to provide a key ring receiving and supporting loop, means on said bent back portion for retaining the key ring disposed in the looped portion 55 against accidental displacement therefrom, said means comprising a substantially inverted U-shaped member pivotally supported on said bent back portion and extending through a slot provided therein, one of the arms of the inverted U-shaped member being in engagement with the intermediate portion of said strip, the other arm 60 extending beyond the outer face of said

bent back portion and providing a means for actuating the same.

65 2. A key ring holder comprising a strip of metal having its upper end provided with attaching means for supporting the same on the belt of a person, the lower portion of said strip being bent back upon itself to provide a key ring receiving and supporting loop, means on said bent back portion for retaining the key ring disposed in the looped portion against accidental displacement therefrom, said means comprising a substantially inverted U-shaped member pivotally supported on the bent back portion and adapted to have one of the arms thereof extending through an elongated slot provided in the bent back portion, the inwardly extending arm having its outer face adapted for engagement with the inner face of the intermediate portion of the strip, the opposite arm of the inverted U-shaped member extending adjacent the outer face of the bent back portion and provided with an enlarged outer end whereby the same may be swung upwardly to move the inwardly disposed arm through said slot and out of engagement with the 90 intermediate portion of the strip.

95 3. A key ring holder comprising a strip of metal having its upper end provided with attaching means for supporting the same on the belt of a person, the lower portion of said strip being bent back upon itself to provide a key ring receiving and supporting loop, means on said bent back portion for retaining the key ring disposed in the looped portion against accidental displacement therefrom, said means comprising a substantially inverted U-shaped member pivotally supported on a pin extending transversely on the bent back portion, one 100 of the arms of the inverted U-shaped member extending through an elongated slot provided in the bent back portion and having the outer face thereof adapted to extend flush against the inner face of the intermediate portion of the strip, the other arm of the inverted U-shaped member being disposed adjacent the outer face of the bent back portion, and an enlarged ball formed on the outer end of the last mentioned arm providing a means whereby said U-shaped member may be swung upwardly so as to cause the inner disposed arm to extend through said slot whereby the outer face of the crown portion of the inverted U-shaped member will extend substantially flush with the inner face of the bent back portion to permit the removal of the key ring holder from the looped portion thereof.

105 In testimony whereof I affix my signature.

ARTHUR E. MILLER.
